INVENTOR,

BY *James B. Ford,
James P. Smith,*

Atty. ATTORNEY

UNITED STATES PATENT OFFICE.

JAMES B. FORD, OF WASHINGTON TOWNSHIP, LOGAN COUNTY, OHIO.

FOUNTAIN-PEN INK-VENDING MACHINE.

Application filed April 19, 1926. Serial No. 103,005.

This invention relates to new and useful improvements in fountain-pen ink vending machines.

It is one of the principal objects of my invention to provide a compact, attractive and dust-proof device or machine in which a fountain-pen may be conveniently inserted for refilling.

It is another object of my invention to provide for attachment to the machine, simple coin-controlled mechanism to permit a fountain-pen to be inserted in the ink reservoir after a coin has been deposited in the coin chute; and thereafter to release the coin from the chute for passage into a coin box below when the pen has been pushed down to its full limit within the ink reservoir.

It is another object of my invention to provide means for preventing the passage of a second coin through the coin chute until the ink reservoir has been closed after its opening by the preceding coin.

It is another object of my invention to automatically restore the coin-actuating mechanism to its locking position when a fountain-pen has been withdrawn from the ink reservoir.

My fountain-pen ink vending machine when made operable by the coin-actuating mechanism will prove a boon both to the manufacturer of fountain pen ink and to a hotel, cigar store or other establishment where it is installed for the purpose of vending that ink. It may, with equal facility, be used without the coin-operating mechanism on an office or home desk.

Other important and incidental objects will be brought out in the following specification and particularly set forth in the subsequently joined claims.

In the accompanying drawings illustrating my invention, Figure 1 is a top plan view of my fountain-pen ink vending machine. Figure 2 is a front view of the same. Figure 3 is a sectional view of said machine taken on the line 3-3 of Figure 1. Figure 4 is a sectional view taken through said machine on the line 4-4 of Figure 1. And Figure 5 is a perspective view of the latch plate and associated mechanism.

Referring to the accompanying drawings for a detailed description of my invention, the numeral 1 designates a base frame which is preferably constructed of brass, with three sides of glass to disclose to view the enclosed mechanism and ink reservoir. The

base frame 1 has a metal bottom and also a metal back, the latter being designated by the numeral 2 and formed with an opening 3 that is closed by a door 4 through which, when open, access may be had to the enclosed parts and deposited coins.

The base frame 1 is closed at its top by a cover plate 5 which is preferably constructed of glass and which is formed at its rear portion with a hole 6 through which there may be inserted the neck of an inverted fountain-pen ink containing bottle 7. Secured to the cover plate 5 by suitable means over the hole 6 therein is a bracket 8 which has a hole 9 that registers with the hole 6 to yieldingly receive the neck of the inverted bottle 7 and to seal the opening around it. (See Figure 3.)

Depending from the cover plate 5 to receive ink from the inverted bottle 7 is a glass ink reservoir 10. For the purpose of inserting into the latter the pen 11 of a fountain-pen to be filled, I have provided the following means. Suitably secured upon the front portion of the cover plate 5, over an opening 12 therein, is a hollow glass cylinder 13 having an integral top 14 which is formed with an opening 15 through which the pen 11 may be inserted.

Free to move vertically in the ink reservoir 10 to close the opening 12 in the cover plate 5 from below, is a gasket 16. The latter, together with a washer 17 below it, is secured by rivets 18 or other suitable fastening means to the bottom of a sleeve 19 into which a fountain-pen is insertible. (See Figures 3 and 4.) The sleeve 19 flares outwardly at its middle portion to form a tapering shoulder 20 which serves as a rest for the inner end 21 of the barrel 21 of the pen.

The sleeve 19 is free to slide over a guide sleeve 22 which is flanged at its upper end for attachment under the top 14 of the glass cylinder 13. At its upper end the sleeve 19 is fastened in a hole in a plate 23, terminating above the latter in a flange 23a. This plate 23 is secured to the upper ends of shafts 24, 24 which are free to move vertically in bearings 25, 25 respectively that are firmly secured in holes in the cover plate 5.

The shafts 24, 24, which project below the horizontal plane of the bottom of the ink reservoir 10, have attached to their lower ends a plate 26. Firmly secured by nuts 27 and 28 in a hole in the bottom of the base frame 1, is a stationary guide rod 29 for

the plate 26 and which projects through a central hole in the latter to form a support above it for the ink reservoir 10.

Surrounding the guide rod 29 between the movable plate 26 and the adjusting nut 27 is a helical spring 30 against the tension of which the plate 26 is adapted to be forced downwardly when the fountain pen 11 is pressed against the gasket 16. Accordingly, 10 by inserting a fountain pen in the sleeve 19 until it engages the gasket 16, and then applying a downward pressure to the barrel 21 of the pen, the shaft frame before described which carries the gasket will be forced downwardly against the tension of the spring 30 to permit that portion of the sleeve which carries the pen point 11 to be immersed in the ink of the reservoir 10. The submerged portion of the sleeve 19 has oppositely disposed ports 19^a through which ink from the reservoir 10 may enter the sleeve to surround the pen 11 therein for entrance through the latter to its barrel 21.

When a fountain-pen has been filled with 25 ink from the reservoir 10, the sleeve 19 which receives the pen may be withdrawn from said reservoir, whereupon the spring 30 will force the plate 26 upwardly. The shafts 24, 24 attached to this plate will then raise the plate 30 23 at their upper ends to elevate the sleeve 19 to a position wherein the gasket 16, which it carries, will seal the opening 12 in the cover plate 5 against the evaporation of ink there-through.

35 For the purpose of making my fountain-pen ink vending machine coin-operated, so that it may be available in hotels, cigar stores and other establishments to fill fountain-pens upon the insertion of a coin, the following 40 means are provided. Fitted to the cover plate 5 over a hole in the rear part of the latter is a coin chute 31 which projects well into the base frame 1 below. (See Figures 2 and 4.) Free to swing like a pendulum about a trans- 45 verse pivot pin 32 in the upper part of the coin chute 31, is a latch plate 33. The toe portion 34 of this plate, which is beveled, is normally maintained under the plate 26 by a light vertical spring 35 having a right 50 angled foot part that is riveted to the bottom of the base frame 1. (See Figure 4.) At the lower corner of the heel part of the latch plate 33 there is formed a lug 36 which is normally in engagement with the spring 35. 55 (See Figures 4 and 5.)

Formed on the plate 33 above the lug 36, is a lug 37 which, when engaged by a coin inserted in the chute 31, will move the latch plate 33 rearwardly a short distance to permit the beveled toe part 34 of the latch plate 33 to come under the edge of the plate 26. The sleeve 19 carrying the pen 11 is now free to be pushed down into the ink reservoir 10 as before described, and during the descent 60 of the plate 26 the latter will cam the foot

part of the latch plate 33 outwardly. The lug 36 which has thus far intercepted the passage of the coin through the chute 31, will now be pressed outwardly to force the light spring 35 against a heavy vertical stop 70 spring 38 which has a right-angled foot part that is secured between the foot part of the spring 35 and the bottom of the base frame 1. (See Figure 4.) The lug 36 now having been pushed out of the chute 31, the coin 75 which it intercepted will drop into a coin box 39 below.

After a fountain-pen has been filled in the ink reservoir 10, the spring 30 will elevate the plate 26 to force the gasket 16 tightly 80 against the opening 12 in the cover plate 5 to seal it. During the upward movement of the plate 26, the spring 35 will force the latch plate 33 upwardly to a position to bring its 85 toe part 34 directly under the edge of the plate 26 for the purpose of locking the machine against operation until another coin has been inserted in the chute 31. (See Figure 2.)

To prevent the passage of a second coin 90 through the chute 31 after the machine has been unlocked by the coin previously inserted, a lug 40 is formed on the latch plate 33 above its toe part 34, so that when the plate 33 is moved outwardly by the first coin, the 95 lug 40 will be moved to a position within the chute 31 to intercept the passage of a second coin through it. When the latch plate is again restored to its locking position, the 100 lug 40 will be withdrawn from the chute 31 to permit another coin to drop upon the lug 37 to unlock the machine as previously described.

From the foregoing description it will be seen that while my fountain-pen ink vending machine may be non-coin controlled, it may be readily converted into a coin-actuated one by applying to it such mechanism as I have just described.

I do not wish to be limited to the details of 110 construction and arrangement herein shown and described, and any changes or modifications may be made therein within the scope of the subjoined claims.

Having described my invention, I claim: 115

1. In a fountain-pen filling device, a reciprocating valve member, a coin chute, a swinging latch plate in said chute formed with a shoulder adapted to engage a lower edge of said valve member, to restrain its 120 downward movement, a beveled corner portion on said latch plate adjacent said shoulder, and a lug on said plate within the chute adapted to be engaged by a descending coin 125 to move the plate outwardly a sufficient distance to bring its beveled corner portion into engagement with the edge of said valve member, for the purpose specified.

2. In a fountain-pen filling device, a reciprocating valve member, a coin chute, a swing- 130

ing latch plate in said chute formed with a shoulder adapted to engage a lower edge of said valve member to restrain its downward movement, a beveled corner portion on said 5 latch plate adjacent said shoulder, a lug on said latch plate within the chute adapted to be engaged by a descending coin to move the plate outwardly a sufficient distance to bring its beveled corner portion into engagement 10 with said edge of the valve member, a second lug on the latch plate below the first lug to

intercept the downward movement of the coin through the chute after it has passed the first lug, and a spring in engagement with the second lug, the second lug adapted to be cammed against said spring to release the coin through the engagement of said edge of the valve member with the beveled corner portion of the latch plate. 15

In witness whereof I have hereunto set 20
my hand this 16th day of April, 1926.

JAMES B. FORD.
